UNITED STATES PATENT OFFICE.

WILLIAM H. WOOD, OF ROCHESTER, NEW YORK.

BUTTON-FASTENER.

SPECIFICATION forming part of Letters Patent No. 295,709, dated March 25, 1884.

Application filed November 13, 1882. (No model.)

To all whom it may concern:

Be it known that I, WILLIAM H. WOOD, of Rochester, Monroe county, New York, have invented a certain new and useful Improvement in Button-Fastenings; and I do hereby declare that the following is a full, clear, and exact description of the same, reference being had to the accompanying drawings.

This invention has for its object the production from wire of a simple and efficient fastener for a shoe-button, the said fastener being adapted to be inserted through an awl-hole in the material from its under side, a partial oscillation of the fastener after its "foot," as I shall term it, has been inserted through the material, carrying the shank of the fastener through the material and bringing the inner side of its head against the under side of the material and the said foot in substantially horizontal position, or slightly inclined downward a little above the face of the material, after which the shank of the button is slipped over the said foot and into the concaved hooked part of the shank of the fastener, the shank being thereafter simultaneously acted upon at a point near the material, and also at the point where the foot and down-turned part of the shank join, and being closed or brought together to inclose the button-shank, the foot, as it is being moved back toward the main part of the shank of the fastener to inclose the shank of the button, being made to bear upon and move over the upper side of the material, thus acting as a clamp to pinch the material between it and the inner side of the head of the fastener and draw the said head snugly up against the under side of the material.

My invention consists of an improved button-fastener composed of a single piece of wire coiled and bent, substantially as shown and described, to form a base, and loop-like inclined shank portions b b' , the part b' being further bent to form a foot, d' , all being constructed and adapted to operate as will be hereinafter described.

My improved fastening may be inserted through an awl or pin hole in the material, the foot of the fastener at such time extending beyond the boundary of the base or head, and thereafter the fastener-shank, as it is closed about the button-shank, causes the unbroken

material to be firmly clamped between the foot and base or head at one side of the main part of the fastener-shank.

Figure 1 represents one of my improved fasteners in perspective. Fig. 2 represents one of my improved fasteners in position below the material in the position it will occupy just as the foot of the fastener is to be inserted through the material. Fig. 3 represents the fastener inserted through the material; Fig. 4, a similar view with the button caught upon the shank of the fastener. Fig. 5 represents the shank of the fastener closed and the foot thrown down and back upon the material, and Fig. 6 represents a pair of pliers by which to bring the two parts of the shank together.

In the manufacture of button-fasteners in accordance with my invention, I take a piece of wire of proper number or gage and stiffness and bend the same into the form represented in Fig. 1, so as to form a head or base, a , a shank, b , having a part of it (marked b') recurved or bent backward to constitute a loop for the reception of the shank c of a button, c' , the wire constituting the fastener being bent or curved at d to form a foot, d' , which normally stands in a position nearly parallel with the inner side of the head or base a , the said foot in practice preferably turning or inclining slightly downward, so that as the part b' and foot are pressed backward toward the part b of the shank, as will be described, the free extremity of the foot will press hard upon the surface of the material m without penetrating the latter. It will be noticed that the so-called "foot" d' is made to project laterally from the shank beyond the boundary or periphery of the head or base, the under side of the said foot being distant from the inner side of the said head in excess of the thickness of the material through which the fastener is to be inserted, so that when inserted and brought into the position Fig. 3 sufficient space will be left between the under side of the said foot and the material for the passage of the shank of the button under the said foot and into the looped part of the shank of the fastener, as shown in Fig. 4. After applying the button as in Fig. 4, the shank of the fastener will be grasped between pliers such as shown in Fig. 6; having thin edges ff ,

and the fastener-shank acted upon by the edges of the pliers at the points marked 2 3, Fig. 4, will be closed to occupy the position Fig. 5, and during such operation the foot d^2 will be 5 brought down against and carried backward toward the main part b of the shank of the fastener, as will be the part b' , and the foot will be made to bear snugly against the surface of the material; and on the arrival of the 10 said foot into a position directly over or above the head or base a the material will be clamped between the said foot and head or base, the passage of the foot inward over the edge of the head or base acting to draw the shank of the 15 fastener farther through the material and the inner side of the head a snugly against and so as to partially embed the said head into the under side of the material m .

When the fastener is to be applied to the 20 material, it is presented at the under side thereof with the free end of the foot d^2 and the inner face of the head a at right angles thereto, and the pointed end of the foot will be pushed through a small round hole made 25 in the said material by an awl or pin, and the point of the said foot having been entered into the material from its under side up to the

junction of the foot with the part b' of the fastener-shank, the fastener will be oscillated or turned over in the direction of the arrow 30 3, thus forcing the shank parts $b' b$, respectively, through the material into the position shown in Fig. 3. After the part d^2 is carried back to clamp the material, as in Fig. 4, the looped part of the shank at the junction of the parts 35 $b' b$ will occupy a nearly central position with relation to the base, so that the strain of the button is exerted on the fastener at its center.

I claim—

As an improved article of manufacture, the 40 button-fastener herein shown and described, it consisting of a single piece of wire bent or coiled to form the base a , and loop-like inclined shank portions $b' b$, the part b' being further bent to form a foot, d^2 , all being constructed and adapted to operate as set forth.

In witness whereof I have hereunto signed my name in the presence of two subscribing witnesses.

WILLIAM H. WOOD.
